Dec. 1541

George B. Owen of New York, N.Y.
Letters Patent No. 1541, dated Feb. 17, 1862.

Procedure referred to in these Letters Patent and making part of the same.

To all whom it may concern:

Be it known that I, George B. Owen, of the City, County and State of New York, have invented or produced a new and original Design for a Clock Base, and I do hereby declare that the following is a full, clear and exact description of the same, reference being had to the accompanying drawings making a part of this specification, in which -

Figure 1. is a face view of a clock case showing my design.

Figure 2. a vertical section of the same, taken in the line x. x. Figure 1.

Figure 3. a horizontal section of a portion of the same, taken in the line y. y. Figure 1.

Similar letters of reference indicate corresponding parts in the several Figures.

The design which constitutes this invention consists of a

Des. 1541

quadrilateral box A, provided with a base B, on the upper edge of which there is a moulding C, formed of a cyma reversa *a*, surmounted by a scotia *b*. The cyma reversa is separated from the top of the base B. by a square or listel *c*, and the cyma reversa and scotia are also separated by a listel *d*. The base B, only extends in front at the sides of the box A.

The front corners of the box A, are not angular, but are formed each of a moulding D, composed of a cymatium *e*, and a listel *f*. See Figure 3.

The box A, has an arched top E. The arched portion *g*, comprises the principal part of the top E, extending nearly the whole width of the box and abutting against short horizontal pieces *h*, *h*.

The front of the top E, has a moulding F, attached which is composed of an ovoli *i*, having a cyma recta *j*, underneath it and a cavetto *k*, underneath the cyma recta.

Between the ovoli *i*, and cyma recta *j*, there is a listel *l*, and there is also a listel *m*, between the cyma recta *j*, and the cavetto *k*. This moulding F, extends around at the sides of box A, as well as at the front, the front moulding being curved to correspond with the curvature of the arched portion *g*, of the top E, as shown clearly in Figure 1. The ovoli *i*, is surmounted by a listel *n*. The moulding F, extends around at the sides of the box A.

Having thus described my invention what I claim as new and desire to secure by Letters Patent, is:-

The general configuration of the parts arranged or disposed as shown and described to form a new and original design for a clock case.

Witnesses.
